UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL DISTRIBUTING MACHINE.

Application filed December 11, 1924. Serial No. 755,245.

This invention relates to typographical machines, such as linotype machines of the general organization represented in U. S. Letters Patent to O. Mergenthaler, No. 436, 5 532, wherein circulating matrices are released from a magazine in the order in which their characters are to appear in print and then assembled in line, the composed line transferred to the face of a mold, the 10 mold filled with molten metal to form a slug or linotype against the matrices which produce the type characters thereon, and the matrices thereafter returned through a distributing mechanism to the magazine from 15 which they started. In some machines, such as the commercial Model 9, where matrices may be drawn from several magazines and mixed together in the same line, the distributing mechanism includes a primary distributor which first sorts the matrices 20 according to font, and a plurality of main distributors which thereafter sort the matrices of the individual fonts according to character and restore them to their proper channels in the magazines. With this type of 25 distributing mechanism, the matrices, after font separation, pass down chutes or tubes and enter so-called lower distributor boxes, from which they are fed one at a time to 30 the main distributors under the control of reciprocating pawls or escapements. In order that these pawls or escapements may 35 cooperate properly with the matrices, the latter are provided in their bottom edges with central notches, which necessarily vary 40 in shape and depth according to the thickness of the individual matrices. Besides adding to the cost of production, such notches in the matrices materially limit the 45 space ordinarily required for the regular font notches and, moreover, seriously weaken the matrices, especially when the latter are formed with other necessary cuts or notches. Furthermore, matrices comprising fonts 50 used on other machines, such as those of the single distributor class, are excluded from use on machines of the multiple distributor class described, since they do not have the required central notches.

55 Primarily, the present invention is intended to obviate the foregoing difficulties and contemplates certain improvements whereby the distributing mechanism may receive and handle matrices of all fonts whether they have or have not the objection-

able central notches referred to. In the preferred embodiment illustrated, each of the lower distributor boxes is cleared of all moving parts, such as the reciprocating pawls or similar devices, and the matrices allowed to 60 pass directly to the pick-up position where they are engaged by the leading ends of the screw-threads and advanced in the usual way along the distributor bar for final distribution. The construction of the boxes is thus 65 greatly simplified and the cost of manufacture reduced to a minimum. The conveying screws are also of special type, the threads thereof being recessed or cut away in their 70 following side faces at points adjacent their receiving ends to present suitable banking surfaces for the matrices as they emerge from the box and to afford ample time for their getaway. Furthermore, means are provided whereby the matrices are maintained 75 upright as they approach the pick-up position and there restrained against rearward displacement and abnormal upward displacement to insure their proper cooperation with the conveying screws.

It has also been found desirable in the use 80 of a distributor box of this character, for reasons which will later be pointed out, to operate the distributing mechanism from an independent source of power.

In the accompanying drawings, the invention has been shown merely in preferred 85 form and by way of example and as applied to the specific type of distributing mechanism indicated. However, many changes 90 and variations may be made therein and in its mode of application, which will still be comprised within its spirit. It is to be understood, therefore, that the invention is 95 not limited to any specific form or embodiment except in so far as such limitations are specified in the claims.

In the accompanying drawings:

Fig. 1 is a side elevation of a linotype machine, partly in section, showing the two 100 driving motors;

Fig. 2 is a side elevation, partly broken away, of the improved distributor box and conveying screws; and

Fig. 3 is a vertical, transverse section, 105 taken on the line 3-3 of Fig. 2.

The matrices X are released from the primary distributor rails (not shown) and dropped at a certain rate, or that determined by the R. P. M. of the primary screws A, 110

into the tubes or chutes A¹, A² arranged in communication with the lower distributor boxes B, through which they are guided and sustained in upright position by the engagement of their projecting ears X¹ with the upper and lower inclined rails B¹, B². Each distributor box directs the matrices to the corresponding main distributor which comprises as usual the longitudinally ribbed 10 or permuted bar C and the set of matrix conveying screws C¹, the arrangement being such that as the matrices emerge from the box they are picked up by the screws and advanced thereby across the horizontal rail 15 extensions B⁴, B⁵ into engagement with the bar C and thence along the same until finally released above their proper magazine channels. The foregoing parts and their mode of operation, except as hereinafter 20 pointed out, are or may be of any approved construction, or as embodied in the commercial Model 9 linotype.

According to the present invention and as before stated, each of the distributor boxes B is cleared of the usual separating or escapement devices and the matrices are allowed to slide uninterruptedly down the inclined rails B¹, B² until checked by contact of their projecting ears with the conveying screws. The latter (see Fig. 2) are preferably of the general type shown in the Guest Patent No. 1,530,491, that is to say, the following side faces of the screw-threads, as distinguished from the leading side faces 25 thereof, and at points adjacent their receiving ends, are cut away or recessed to present vertical circumferential surfaces C² extending about half-way around the first convolution. These surfaces C² afford desirable banking surfaces for the matrices and, as a matter of fact, constitute stops which, under normal conditions, are presented to the projecting ears of the matrices as they emerge uninterruptedly, one after another, from the box. The matrices are thus 30 squarely arrested at the desired point in the pick-up zone, but inasmuch as they might have a tendency to recoil or rebound because of their impact with the screws and 35 stop the distributor, the rails B¹, B² are provided with shoulders or abutments B³, which serve to restrain the matrices against rearward displacement when they reach the pick-up position. It will be noted that the 40 restraining shoulders B³ are disposed in a vertical plane lying between that of the banking surfaces C² and the tapered leading ends C³ of the screw-threads, so that the individual matrices are caused to pass beyond the screw ends C³ and be deposited 45 upon the rail extensions B⁴, where they may rest momentarily or until their projecting ears are engaged by the leading side faces of the screw-threads. With this arrangement, 50 a matrix has ample room and time to reach

the pick-up position before it is carried away by the screws, the shoulders B³ being located sufficiently far from the tapered ends C³ of the screw-threads and the banking surfaces C² being of sufficient circumferential extent to provide for any slight variation in the rate of delivery of the matrices to the screws, due to friction or other delaying influences. It will now be seen that a matrix when released by the primary distributor will pass endwise through one or the other of the chutes A¹, A², enter the proper box B and be straightened up at X² (Fig. 2), so as to engage the rails B¹, B², and then slide downwardly facewise along the rails directly into contact with the banking surfaces C² of the screws. These surfaces C² are, of course, properly coordinated so as to stand in the same vertical plane and arrest the matrix squarely in upright position. Any liability to rebound or deflection is obviated by the shoulders B³ which thus maintain the matrix in proper position to be picked up by the leading ends of the screw-threads. It may be noted that the shoulders B³ are located (as shown in Fig. 2) at such distance in advance of the banking surfaces C² that the thickest matrix ears will be accommodated and matrices of all sizes guided accurately to the pick-up position. 55

Means are also provided whereby a matrix gravitating toward the pick-up position will be maintained upright at all times. To this end, the lower edges of the rails B⁴ are extended in parallelism with the upper inclined edges thereof to a point slightly beyond the vertical plane of the shoulders B³ and are located at such distance from said upper edges as to cooperate with the lower projecting ears of the matrices and prevent the latter from tilting or swinging forwardly at their lower ends. Extensions B⁶ are in this way formed on the rails B¹, and they serve the additional purpose of preventing a matrix when it reaches the pick-up position 100 from being displaced above the shoulders B³, as might otherwise result from its frictional contact with the rotating banking surfaces C². 105

The matrix conveying screws of the primary and main distributors are driven at the same speed so that the individual matrices will follow one another through the distributor boxes a certain distance apart and be successively picked up by the screws 110 C¹. The timing of the parts is such that, under normal conditions, the recessed portions of the screws C¹ will receive the matrices one after another, the rate of their delivery to the pick-up position necessarily 115 corresponding to the rate of rotation of the screws. 120

In the commercial linotype machines (see Fig. 1), the usual driving mechanism includes the cam shaft F and intermediate 125 130

shaft G, the former being intermittently driven from the electric motor E through the clutch member F¹ and the drive pulley F², and the latter being constantly driven from the pulley F² by belting G¹. Ordinarily, the distributor screws are driven approximately at the rate of 300 R. P. M., so that the matrices will drop from the primary distributor at the rate of five a second. Accordingly, and due to the distance between the primary and main distributors, several matrices are usually in course of gravitation at the same time, and hence a slowing up of the distributor screws might cause the matrices to pile up in the distributor boxes and stop the distributing mechanism. Heretofore, it has been the custom to operate the distributing mechanism from the intermediate shaft G, which, as just stated, is constantly driven from the motor E. However, in carrying out this invention, it is proposed to operate the distributing mechanism by a separate motor D, which is entirely independent of the regular motor E. As shown in Fig. 1, the motor D is mounted adjacent the distributor bracket O on a support D¹ and drives the primary and main distributor screws through suitable belting D² (indicated in dotted lines). As a result of this arrangement, the distributing mechanism is operated continuously and uniformly at all times to insure the steady and uninterrupted distribution of the matrices and is not affected in any way by the behavior of the regular motor E which is frequently slowed up from different causes, such as the sending through of a tight line, etc.

Having thus described my invention, its construction and mode of operation, what I claim and desire to secure by Letters Patent of the United States, is as follows:

1. In a typographical distributing mechanism comprising a distributor bar and a set of matrix conveying screws, the combination of guiding means to direct the matrices uninterruptedly into position to be picked up by the screws, and means for restraining the matrices against rearward displacement when they reach such position.

2. In a typographical distributing mechanism comprising a distributor bar and a set of matrix conveying screws, the combination of a distributor box through which the matrices pass by gravity uninterruptedly into position to be picked up by the screws, and means arranged to restrain the matrices against rearward displacement when they reach such position.

3. In a typographical distributing mechanism comprising a distributor bar and a set of matrix conveying screws, the combination of a distributor box through which matrices pass by gravity, upper and lower guide rails arranged within said box to co-

operate with the projecting ears of the matrices and direct them uninterruptedly into position to be picked up by the screws, and shoulders formed on said rails to restrain the matrices against rearward displacement when they reach the pick-up position.

4. In a typographical distributing mechanism comprising a distributor bar and a set of matrix conveying screws, the combination of a distributor box through which matrices pass by gravity uninterruptedly into position to be picked up by the screws, and means for restraining the matrices against abnormal upward displacement when they reach such position.

5. In a typographical distributing mechanism comprising a distributor bar and a set of matrix conveying screws, the combination of a distributor box through which matrices pass by gravity, upper and lower guide rails arranged within said box to direct the matrices into position to be picked up by the screws, and extensions formed on said upper rails to restrain the matrices against abnormal upward displacement when they reach such position.

6. In a typographical distributing mechanism comprising a distributor bar and a set of matrix conveying screws, the combination of a distributor box through which matrices pass by gravity into position to be picked up by the screws, means for maintaining the matrices upright as they approach the pick-up position, and means for restraining them against abnormal displacement when they reach such position.

7. In a typographical distributing mechanism comprising a distributor bar and a set of matrix conveying screws formed with matrix banking surfaces, the combination of a distributor box through which the matrices pass by gravity uninterruptedly into position to be picked up by the screws, means for maintaining the matrices upright as they approach the pick-up position, and shoulders for restraining said matrices against rearward displacement when they reach such position.

8. In a typographical distributing mechanism, the combination of a distributor box through which matrices pass uninterruptedly by gravity, and a set of matrix conveying screws arranged to receive the matrices therefrom, the threads of said screws being cut away in their following side faces at points adjacent their receiving ends to present banking surfaces for the matrices as they emerge from the box.

9. In a typographical distributing mechanism, the combination of a distributor box through which matrices pass uninterruptedly by gravity, and a set of matrix conveying screws arranged to pick up the matrices as they issue from the box, the first convolution of the screw-threads being formed

with vertical circumferential banking surfaces adapted to arrest the matrices in the pick-up zone.

10. In a typographical distributing mechanism comprising a distributor bar and a set of matrix conveying screws, the combination of a distributor box through which matrices pass by gravity, and upper and lower inclined guide rails arranged within 10 said box to direct the matrices into position to be picked up by the screws, the lower edges of said upper rails being extended in parallelism with the upper inclined edges thereof to maintain the individual matrices upright until they reach the 15 pick-up position.

11. In a typographical distributing mechanism, the combination of a distributor box through which matrices pass by gravity, a 20 set of matrix conveying screws having the following side faces of their threads for a portion of the first convolution cut away so as to present vertical circumferential banking surfaces for the matrices, and abutments arranged in a vertical plane in advance of said banking surfaces to cooperate with the projecting ears of the matrices in 25 the manner set forth.

12. In a typographical distributing mechanism, the combination of a set of matrix conveying screws having the following side 30 faces of their respective threads cut away from points adjacent the entrance of the grooves to present vertical circumferential banking surfaces for the matrices, a distributor box, guide rails arranged therein to direct the matrices to the said banking surfaces, and shoulders formed on said rails and arranged in a vertical plane lying with 35 in the cut-away portions of the threads for restraining the matrices against rearward displacement when they are arrested by the screw banking surfaces.

13. In a typographical distributing mechanism, the combination of a set of matrix conveying screws formed with matrix banking surfaces, a distributor box, guide rails arranged therein to direct the matrices into engagement with said banking surfaces, and 40 shoulders formed on said rails to restrain the matrices against rearward displacement when arrested by the screw banking surfaces, the said shoulders being disposed in a vertical plane lying between the leading ends 45 of the screw-threads and said banking surfaces.

14. In a typographical distributing machine, the combination of a primary distributor including a set of matrix conveying

screws, a plurality of main distributors each 60 likewise comprising a set of matrix conveying screws, means for driving the screws of the primary and main distributors in proper synchronism, distributor boxes arranged to receive the matrices from the primary distributor and guide them into position to be picked up by the screws of the main distributors, the latter screws being formed at their receiving ends with vertical circumferential banking surfaces to arrest the matrices as 70 they issue from the respective distributor boxes.

15. In a typographical distributing machine, the combination of a primary distributor, including a set of matrix conveying 75 screws, a plurality of main distributors each likewise comprising a set of matrix conveying screws, the latter being formed with matrix banking surfaces in the following 80 side faces of their respective screw-threads 85 at points adjacent their receiving ends, means for driving the screws of the primary and main distributors in proper synchronism, distributor boxes arranged to receive the matrices from the primary distributor and guide them into position to be picked up by the screws of the main distributors, and shoulders, disposed in a vertical plane lying between the leading ends of the screw-threads and said banking surfaces, for restraining the matrices when in the pick-up 90 position against rearward displacement.

16. In a linotype machine, the combination of the main cam shaft, and the distributing mechanism, with means for driving 95 the said cam shaft, and separate and independent means for operating the distributing mechanism, the two said means functioning simultaneously in operating their respective parts.

17. In a linotype machine, the combination of the main cam shaft and the distributing mechanism comprising a primary distributor and a plurality of main distributors, with a motor for driving the cam shaft, and a separate motor for operating the distributing mechanism, the two said motors functioning simultaneously in driving their respective parts.

18. A typographical distributing mechanism according to claim 14, characterized by the fact that it is operated from an independent source of power, for the purpose described.

In testimony whereof, I have affixed my 115 signature hereto.

DAVID S. KENNEDY.
